UNITED STATES PATENT OFFICE.

LILLIE GENEVIEVE STEEN, OF PITTSBURGH, PENNSYLVANIA.

PUZZLE.

1,137,805.

Specification of Letters Patent.

Patented May 4, 1915.

Application filed November 22, 1913. Serial No. 802,581.

To all whom it may concern:

Be it known that I, LILLIE GENEVIEVE STEEN, a citizen of the United States of America, residing at Pittsburgh, in the 5 county of Allegheny and State of Pennsylvania, have invented certain new and useful Improvements in Puzzles, of which the following is a specification, reference being had therein to the accompanying drawing.

This invention relates to puzzles, and has for its object to provide in a manner as hereinafter set forth, a device of such class including a plurality of shiftable elements 15 adapted to be housed to complete the representation of the head of a miniature figure. By way of example, a figure representing "Humpty Dumpty" sitting on a wall.

Further objects of the invention are to 20 provide, in a manner as hereinafter set forth, a puzzle which is simple in its construction and arrangement, durable, amusing, requiring a certain amount of dexterity for the purpose of housing the shiftable elements 25 to complete the head of the miniature figure, readily set up and inexpensive to manufacture.

With the foregoing and other objects in view, the invention consists of the novel 30 construction, combination and arrangement of parts, as hereinafter more specifically described and illustrated in the accompanying drawings, wherein is shown an embodiment of the invention, but it is to be understood 35 that changes, variations and modifications can be resorted to which come within the scope of the claims hereunto appended.

In the drawings wherein like reference 40 characters denote corresponding parts throughout the several views:—Figure 1 is a front elevation of a puzzle in accordance with this invention with the shiftable elements housed to complete the head of the miniature figure, Fig. 2 is a vertical sectional view thereof, Fig. 3 is a plan view with the cover removed and illustrating the shiftable elements out of position, Fig. 4 is a detail broken away of the receptacle, Fig. 5 is an inverted plan view broken away of the puzzle, Fig. 6 is a cross sectional view of the 50 puzzle.

In describing the invention I shall refer to the drawing, in which similar reference characters designate corresponding parts 55 throughout the several views and in which 1 indicates a base of plate like design having

a cylindrical block 2 secured to the central portion thereof and surrounding this block to rotate therearound and also resting on the base 1 is a ring member 3, the outer periphery of which is toothed or serrated as indicated at 4.

Secured to the upper face of the ring member 3 is a plate or the like 6 which forms the bottom of an inclosure, said plate being provided with a central opening through which the block 2 projects. Secured to the under face of said plate 6 immediately adjacent the outer peripheral edge thereof and arranged at predetermined points thereon are the lugs 9 to which are secured the upright supporting strips 8. These upright supporting strips project some distance above the plate 6 and have secured thereto a rim 7, the latter having its lower edge spaced slightly above the plane of the upper face of said plate 6, as clearly indicated in Figs. 2, 4 and 6 of the drawing. The plate 6 which is rotatable, being mounted on the rotatable ring 3, forms with the rim therearound an inclosure or receptacle, the purpose of which will be hereinafter and more particularly set forth.

Secured to the upper face of the block 2 by means of fastening devices 12, the latter also securing said block to the base 1, is an additional plate member 10 which superposes the plate 6 and which is spaced from the latter as well as from the lower edge of the rim 7, as clearly shown in Figs. 2 and 6 of the drawing. This latter plate 10 has a picture painted, drawn or otherwise inscribed thereon, the purpose of which being hereinafter set forth.

The base 1 may be designed rectangularly 95 or otherwise, as desired, and arranged in connection therewith are the walls 28 which together with said base form a casing for the device. The top of this casing is designated in the drawing as 13 and is preferably 100 formed of glass or other transparent material, so that the movable objects within the inclosure will be readily observed. This base plate 1 is also provided with two enlarged semi-circular openings 14 through 105 which the fingers may be disposed to shift the movable elements of the device when desired. A rim or band 11 is also provided in connection with the walls 28 which forms an ornamental support for said transparent 110 top 13.

Secured to the inner periphery of the rim

7 is a corrugated rim or band 14^a and extending inwardly therefrom at predetermined points are the projections 15, which may be said to be obstacles. The purpose 5 thereof will be hereinafter more particularly set forth.

Mounted on the top face of the plate 10 is a block or the like 16 which is designed to represent a wall and formed integral with 10 this block or otherwise supported thereon and arranged in a plane just above the upper face of the block 16 forming a wall is a plate like member 17 which is designed to represent the body of a miniature figure, 15 such as "Humpty Dumpty". A block 18 is also provided, the latter being designed to form an enlarged head member for the figure and secured to the body plate 17. This head member is held in position with respect to the wall 16 by means of a coil 20 spring 20, as clearly shown in Figs. 2 and 3 of the drawing. The block 18 which forms this enlarged head is of a greater thickness than the block 16 representing the wall and 25 thus the body 17 of the figure has the appearance of sitting on the wall with the lower portion thereof projecting therefrom.

The block 18 which forms the head of the figure is provided with a vertical pocket or 30 the like 21 which terminates at its outer end in an angular recess 22. A globular member 27 is provided within the inclosure and adapted for reception in the pocket 21, the same being shown in Fig. 3 as resting against 35 the corrugated rim 14^a. The portion of the block 18 which is cutaway to form the recess 22 is separated into a series of shiftable elements as indicated by the reference characters 23, 24, 25 and 26, and when these elements are shifted in place with respect to 40 one another and with respect to the recess 22, the head of the miniature figure is completed, as illustrated in Fig. 1 of the drawing. It is the object of the puzzle to position 45 these shiftable elements in such position with respect to one another as to complete the formation of the head of the figure. In order to aid in this respect and also to form obstacles in the working of the puzzle are 50 the deflectors 15, heretofore referred to. The globular member 27 would of course also aid in shifting the elements for solving the puzzle. In order to solve the puzzle, the member 27 is first shifted into the pocket 21, after which the elements 23, 24, 25 and 26 55 are shifted about over the plate 10 to enter the recess 22 in proper relation to one another. In order to accomplish the results, the base 1 may be tilted to various degrees 60 in order to cause the shifting of the elements, or the base may be retained stationary while the movable parts may be rotated or partially rotated by projecting the fingers of the hand through the openings 14.

65 From the foregoing description of the

construction of my improved device, the manner of placing the same in operation will be readily understood and it will be seen that I have provided a simple, inexpensive and efficient means for carrying out the objects of the invention.

While I have particularly described the elements best adapted to perform the functions set forth, it is obvious that various changes in form, proportion and in the 75 minor details of construction may be resorted to, without departing from the spirit and scope of the appended claims, or sacrificing any of the principles of the invention.

What I claim is:—

1. A puzzle comprising a resiliently connected miniature figure having its head cut away to provide a recess, supporting means for said figure, and a series of shiftable elements adapted to be housed in said recess to 85 complete the head of said figure.

2. A puzzle comprising a resiliently connected miniature figure having its head cut away to provide a recess, supporting means for said figure, a series of shiftable elements 90 adapted to be housed in said recess to complete the head of said figure, a receptacle for said supporting means, and means whereby said receptacle and plate can be shifted independently of each other. 95

3. A puzzle comprising a resiliently connected miniature figure having its head cut away to provide a recess, supporting means for said figure, a series of shiftable elements adapted to be housed in said recess to complete the head of said figure, a receptacle for said supporting means, means whereby said receptacle and plate can be shifted independently of each other, a corrugated band within said receptacle above said supporting means, and deflectors projecting inwardly from said supporting means. 10

4. A puzzle comprising a resiliently connected miniature figure having its head cut away to provide a recess, supporting means 11 for said figure, a series of shiftable elements adapted to be housed in said recess to complete the head of said figure, a receptacle for said supporting means, means whereby said receptacle and plate can be shifted independently of each other, a corrugated band within said receptacle above said supporting means, deflectors projecting inwardly from said supporting means, said head provided with a pocket, and a spherical 12 member adapted to be lodged in said pocket.

5. A puzzle comprising a receptacle, a plate arranged therein, means whereby said receptacle and plate can be shifted independently of each other, a miniature figure 12 connected with said plate and having its head cut away to provide a recess, and a series of shiftable elements adapted to be lodged in said recess to complete the head.

6. A puzzle comprising a receptacle, a 13

plate arranged therein, means whereby said receptacle and plate can be shifted independently of each other, a miniature figure connected with said plate and having its head cut away to provide a recess, a series of shiftable elements adapted to be lodged in said recess to complete the head, a corrugated band arranged within said receptacle

above said plate, and deflectors projecting inwardly from said band. ¹⁰

In testimony whereof I affix my signature in the presence of two witnesses.

LILLIE GENEVIEVE STEEN.
